WINDING SPINDLE

Ernest Koella, Rockford, Tenn., assignor to Rockford Manufacturing Company, Rockford, Tenn., a corporation of Tennessee

Application February 5, 1943, Serial No. 474,857

2 Claims. (Cl. 242—35)

This invention relates to an improvement in winding spindles of the character used in winding machines, for supporting yarn packages, either of cone or of tube shape.

Winding spindles of the character used heretofore have been constructed for supporting one cone or tube each, that is removably disposed thereon, and must be replaced when it is wound to the proper size. During the winding operation with such spindles, the yarn frequently jumps 10 the yarn guide and accumulates between the washer and the yarn package, being thus wound around the spindle. This accumulated waste decreases production because the operator must stop the winding operation on this particular spindle and unravel the bunch of yarn and then start the operation again by fastening the yarn on the cone or tube or other support on the spindle. Also in doffing, after taking off the finished package, the operator must clean the 20 spindle free of all bunched and wound up yarn, no matter how small, because the paper tube or cone cannot be inserted to its proper place unless the spindle is clean throughout its length.

The object of this invention is to improve the 25 construction of the spindle to prevent the accumulation of waste therearound between the washer and the package, and to eliminate the necessary winding required for removal of the accumulation on the spindle.

This object is accomplished by providing a convex washer of enlarged size on the spindle in position for abutment of the package support or tube thereagainst. The large size of this convex washer prevents the loose end of the yarn from slipping over the selvedge of the package and accumulating on the spindle forming a bunch of yarn. By the large diameter of the washer and its divergent peripheral wall, a broken end of the 40 yarn would be thrown outward by centrifugal force to the winding surface of the package, instead of falling onto the spindle between the washer and the package.

I have shown a preferred embodiment of the 45 invention in the accompanying drawing in which:

Fig. 1 is a side elevation of a winding spindle having this invention applied thereto; and

Fig. 2 is a detail side elevation thereof, partly 50 in section.

The spindle shown is designated generally by the numeral 1 and is of a general character well-known in the art, having an enlarged shank or butt 2 adapted to be pivotally mounted in the usual manner on the end of an arm of a winding

machine, to support a yarn package thereon. The spindle 1 is disposed in inclined or parallel relation with respect to the periphery of a drive roll against which the package bears.

The package is designated generally by the numeral 3 and is formed on a cone or tube 4 removably fitted over the spindle 1 and rotatable relative thereto by surface contact of the package against the drive roll therefor.

At one end of the spindle 1, a washer 5 is normally provided to form a stop for the tube 4 of the yarn package. I have provided an enlarged washer 6, having a peripheral wall 7 mounted on the spindle 1. The washer 6 with its wall 7 are shaped generally convex toward the yarn package, and this washer provides a flat surface at the end of the package with the wall 7 extending divergently therefrom, substantially in cone shape, providing the convex shape referred to. The washer 6 is shown as secured in place on the spindle by being fitted directly thereover and abutting against the usual stop washer 5 to which the side face of the washer 6 is welded. However, the washer 6 may be secured in any other desired or convenient manner to the spindle without the necessity for the washer 5.

The spindle is used in the usual manner of spindles that are employed in friction or drum-drive winding machines for forming a tube or cone 30 thereon. During the winding operation, the convex shape of the washer 6 with its wall 7, prevents the accumulation of yarn between the washer and the end of the package around the spindle. This washer does not permit the loose end of the yarn 35 to slip over the selvedge of the package and accumulate in a bunch on the spindle. The large diameter of the peripheral wall 7 causes the broken end of the yarn to be thrown back onto the winding surface of the tube or cone instead of falling down on the spindle as has been the effect heretofore of using smaller flat washers. This eliminates the large amount of back-winding that has been required and keeps the spindle 40 clean, thus effecting a material saving in time both of the operator and the machine particularly in doffing, as well as in operation.

This improvement has been used over several months on many spindles of a winding machine and has been found to be a great improvement in saving waste and labor, and has materially increased production.

I claim:

1. A winding device comprising an enlarged shank and a reduced spindle having one end fixed 55 to the shank and projecting outwardly therefrom

to receive a yarn package thereon for rotation relative thereto, and a washer surrounding an end of the spindle and the shank and having a flat center portion fixed to the spindle normal to the axis of the spindle and of a size adapted to extend throughout the area of the yarn package support, said washer having a frusto-conical wall surrounding said flat center portion and forming a convex shape facing toward the package.

2. A winding device comprising a shank and a spindle having one end fixed to the shank and projecting outwardly therefrom to receive a yarn

package thereon for rotation relative thereto, a flat washer surrounding an end of the spindle adjacent the shank and fixed thereto, and an enlarged washer having a flat center portion abutting against the first-mentioned washer normal to the axis of the spindle and fixed thereto and of substantial diameter adapted to extend throughout the area of the yarn package support, said enlarged washer having a frusto-conical wall surrounding said flat center portion and forming a convex shape in position to face toward the package.

ERNEST KOELLA.
